UNITED STATES PATENT OFFICE.

WILLIAM F. SCHACHT, OF GOSHEN, INDIANA.

HAIR-CURLER.

No. 876,402.

Specification of Letters Patent.

Patented Jan. 14, 1908.

Application filed April 8, 1907. Serial No. 367,043.

To all whom it may concern:

Be it known that I, WILLIAM F. SCHACHT, a citizen of the United States, residing at Goshen, in the county of Elkhart and State 5 of Indiana, have invented a new and useful Hair-Curler, of which the following is a specification.

This invention relates to a hair curler around which is to be tightly wrapped a lock 10 of hair, the ends of the curler being then joined, to prevent the hair from uncoiling, and allowed to remain for an indefinite time, or until the hair is curled.

The object of the invention is to provide a 15 simple, cheap and efficient curler formed of soft rubber, rubber compound or other resilient material, somewhat in the shape of a pin, pointed at one end and having a head at the other end, provided with an eye 20 through which the pointed end is passed after the hair has been wound on the curler.

In the accompanying drawing: Figure 1 is a view of the hair curler as seen from one 25 side. Fig. 2 is a cross section on the line 2—2 of Fig. 1, enlarged. Fig. 3 is a perspective view of the hair curler applied.

Similar numerals indicate the same parts on all the figures.

The hair curler comprises a stem 1, a tip 2, 30 and a head 3, molded or otherwise made of soft rubber or other resilient material. The stem and tip may be semi-circular in cross section, as shown, and of such length and width as will best attain the object sought.

The hair curler is preferably made with a 35 slight taper from the head 3 to the junction of the stem 1 with the tip 2, whence the reduction in size is more pronounced, finishing as a blunt point 4 at the end of the tip. On 40 one side of the tip 2, which for convenience of description, will be called the top, a plurality of longitudinally spaced studs 5 project a short distance above the surface as shown, so that when the hair curler is looped as in 45 Fig. 3, and the tip 2 passed through an aperture 6 in the head 3, one or another of the studs 5 will prevent the withdrawal of the tip by the resiliency of the material. The shape of the aperture 6 is similar to the stem 50 1 but slightly smaller so that the tip when

pulled therethrough will be held tightly in place by the enlargement of the aperture owing to the resiliency of the head 3.

Projecting from the head on the side opposite the stem 1 is a finger piece 7, integral 55 with the head 3, which is held by one hand while pulling the tip 2 through the aperture 4 with the other hand. The finger piece 7 may have a piece of cloth 8 or other non-resilient material incorporated therewith to 60 strengthen it if thought best. The head 3 is flat on the top and bottom, and curved on the sides; its thickness is that of the stem 1. This shape and size is optional and may be changed if desired. 65

In applying the hair curler, a lock of hair is wound tightly on the stem 1, after which the tip 2 is pushed into the aperture 6 and its end caught by the fingers and drawn therethrough until the loop, formed by the bent stem, is sufficiently tight. The friction of the tip in the aperture is sufficient to hold it in place when a small lock of hair is wound on the stem, but to insure its retention at all times, it is thought best to place the studs 5 70 75 on the tip. After the hair has curled, the tip is withdrawn from the aperture and the curler slipped endwise from the hair without uncoiling it.

Having thus described the invention what 80 is claimed is:—

1. As an article of manufacture, a hair curler made of soft resilient material in the form of a pin, having a tapered tip, a perforated head and a finger piece projecting 85 from the head.

2. As an article of manufacture, a hair curler made of soft resilient material in the form of a pin, having a perforated head, a tapered tip provided on one side with a plurality of longitudinally spaced lugs, and a finger piece projecting from said head. 90

In testimony that I claim the foregoing as my own, I have hereto affixed my signature in the presence of two witnesses.

WILLIAM F. SCHACHT.
